UNITED STATES PATENT OFFICE.

JOHN B. FITZPATRICK, OF NEW YORK, N. Y.

HATPIN.

1,400,147.

Specification of Letters Patent. Patented Dec. 13, 1921.

Application filed April 8, 1921. Serial No. 459,686.

To all whom it may concern:

Be it known that I, JOHN B. FITZPATRICK, a citizen of the United States, residing at New York city, borough of Manhattan, in 5 the county and State of New York, have invented a certain new and useful Hatpin, of which the following is a specification.

This invention relates to hat pins and the object of the invention is to provide a hat 10 pin of variable length, whereby it is adapted for use with hats of different sizes, without exposing unsightly and dangerous points when worn in conjunction with hats of the smaller sizes.

15 Another object of the invention is to provide a hat pin construction, wherein the point of the pin will be housed and concealed within a guard carried by the hat.

It has been heretofore suggested to provide 20 detachable guards for hat pins and after a relatively long pin had been thrust through the crown of the hat, the guard was adapted to be slipped over the point of the pin and frictionally held in place thereon 25 for the purpose of protecting persons other than the wearer from injury by the projecting point of such a pin. In all of these prior devices, however, the guard over the point of such pin has been supported directly upon the pin and it has been found 30 in practice that guards so supported either eventually become lost or the wearer tires of adjusting the guard each time the hat is donned and discontinues the use of the same. 35 For these reasons, hat pin guards of the character specified have not gone into extensive use.

In carrying out the present invention, a hat pin guard is mounted in a relatively 40 permanent manner directly upon the crown of the hat, so that it cannot become lost nor can the wearer forget to apply the guard and employ the pin in a manner in which the point thereof is exposed.

45 Another object of this invention is to provide means whereby the pin may be locked in position after it has been operatively associated with the hat, whereby it is maintained against loss or displacement until 50 manually removed.

A further object of the invention is to provide means associated with a hat whereby the pin may be brought into coöperative relation therewith without unduly marring

the hat. It is the usual practice for ladies to 55 thrust the hat pin through different portions of the hat each time the pin is inserted, so that after a relatively short time, a number of unsightly perforations or holes are visible, which necessitate the discarding of the hat. 60 When the present invention is employed, this damage to a hat is entirely overcome.

Features of the invention, other than those adverted to will be apparent from the hereinafter description and claims, when read in 65 conjunction with the accompanying drawings.

The accompanying drawings illustrate one practical embodiment of the invention, but the construction therein shown is to be understood 70 as illustrative, only, and not as defining the limits of the invention.

Figure 1 is a central section through a hat showing a hat pin embodying the present invention associated therewith. 75

Fig. 2 is a central section of the hat guard means adapted to be associated with the point of the pin; and,

Fig. 3 illustrates, partly in section and partly in elevation, the head of the pin and 80 the means whereby the same may be locked in position relative to the hat.

Referring to the drawings, 1 designates a hat and 2 denotes the hat pin generally. As shown, the pin is in two parts 3 and 4, which 85 are adapted to telescope into one another. That is to say, the part 4 is made tubular and the part 3 telescoped into the part 4, as clearly shown in Fig. 1.

In practice, the parts are so associated 90 that they will have a relative sliding fit, with sufficient friction to maintain them in any adjustment into which they may be brought. The exterior end of the part 3 is pointed as at 5 to enable it to readily pass 95 through the hair, while the inner end of the tubular part 4 is tapered as at 6 for the same purpose. The other end of the tubular part is provided with any suitable form of head 7, which, in practice, is preferably of 100 ornamental character.

By construction a hat pin as described of two telescoping parts, the same is adapted for use with hats of different crown sizes, it being manifest that the length of the pin 105 may be regulated by exposing a greater or lesser portion of the part 3, beyond the end of the tubular part 4. A pin of this charac-

ter may be employed in the manner usual in hat pin usage, but in the preferred form of the invention, means is associated with the hat to protect the point of the pin and also 5 to lock the pin in position, while the hat is being worn.

The pin retaining means is clearly shown in Fig. 3 of the drawings as embodying a retainer 8. This retainer 8 may be formed 10 of sheet metal and is provided with a cupped portion 9 and an exteriorly threaded tubular shank 10. In associating the retainer with a hat, the crown of the hat is perforated, so as to permit the threaded 15 shank 10 to extend through the wall of the crown and the lock nut 11 is thereafter screwed upon the threaded shank interiorly of the crown for the purpose of rigidly securing the retainer thereto. The interior 20 bore of the shank 10 is made of a size to permit of the passage of the tubular portion 4 of the hat pin therethrough, while the cupped portion 9 is constructed of such size as to receive a boss 12, formed at the base 25 of the head 7. This boss is provided with a projection 13 and the interior of the cup portion 9 is provided with a helical groove 14, so that after the hat pin has been passed through the shank 10, the projection 13 may 30 be brought into engagement with the slot 14 and the head 7, thereupon rotated to cause the projection 13 to traverse the slot 14, and thereby lock the hat pin in position.

The hat pin will manifestly be retained in 35 such position until the head 7 is rotated in a retrograde direction to disengage the projection 13 from the slot 14 and permit of the removal of the pin.

I am aware that retaining means of the 40 character specified may be employed with hat pins of the usual construction, *i. e.*, hat pins formed in one piece and without the extendable feature described and, accordingly, the present invention, so far as the 45 retainer is concerned, is not restricted for use with an extendible pin.

Fig. 2 of the drawings clearly illustrates the pin point protecting means, which, in practice, is mounted on the opposite side of the 50 crown from that occupied by the retainer. The protector embodies an exteriorly threaded shank 15, provided at one end with a flared mouth 16 and in associating the protector with the crown, the 55 crown is perforated so that the shank 15 may be passed through the wall of the crown from the inside thereof and receive a lock nut 17 exteriorly of the crown. The lock nut 17 may conveniently be made hollow, and, in practice, is preferably ornamental in character and of substantially the same size and configuration as the head 7 of the hat pin, so that when the head 7 of the pin occupies a position on one side of the 60 hat, the enlarged head 18 of the lock nut 65

17 will occupy the opposite side of the hat and impart a balanced ornamental appearance to the hat.

When assembling the parts on a hat, the threaded shank 15 and the threaded shank 70 10 are mounted in substantial alinement, so that a pin thrust through the threaded shank 10 may extend through the hair of the wearer and project into the threaded shank 15. In this manner, the hat pin is firmly 75 associated with the hat, while the point of the pin is housed within the protector in concealed position, wherein it can do no damage.

The present invention may be readily associated with hats of any kind, and the collapsible feature of the pin enables the length of the pin to be regulated for coöperation with hats of any size within wide limits. I am aware, however, that the protecting 85 means of this invention may be employed to advantage with pins of the conventional type, and, accordingly, the present invention, so far as the protector is concerned is not limited to employment with retaining 90 means or pin construction of the character shown in the drawings.

It has heretofore been noted that the shank 15 is provided with a flared mouth 16. This feature facilitates the bringing 95 of the point of the pin into coöoperative relation with the protector, and, in practice, this flaring mouth may be made of any desired size, so that time need not be lost in bringing the point of the pin into coöperation with the protecting means. The outer periphery of the flared mouth is preferably 100 rolled or beaded over so as to provide a smooth surface, which will not catch the hair.

It will be apparent from the foregoing description of the invention that the same embodies many novel features of construction, some of which may be employed to advantage without necessarily employing 110 all. Accordingly, the present invention is to be understood as not restricted to the complete preferred embodiment shown in the drawings, but is to be construed as broadly novel as is commensurate with the 115 appended claims.

Having thus fully described the invention, what I claim as new and desire to secure by Letters Patent is:

1. A construction of the character described embodying a hat pin comprising a plurality of smooth telescoping sections provided with smooth uninterrupted cylindrical exteriors, and having a frictional sliding fit with one another, permitting of adjustment 120 of the length of the pin, and the inner section being of such length that it will at all times project beyond the outer section.

2. A construction of the character described embodying a hat pin comprising a 130

tubular section having a smooth, uninterrupted, interior, cylindrical bore, and exteriorly tapered at one end, a head fixed on the opposite end of said section, and a pointed solid shank provided with a smooth surface and telescoping with a frictional sliding fit into the tapered end of the tubular section, whereby the length of the hat pin can be changed at will, said solid shank 10 being of such length that its pointed end will at all times project beyond the tapered end of the tubular section.

3. A construction of the character described embodying a protector adapted to be mounted on a hat and provided interiorly with a smooth walled chamber opening into the interior of the hat and closed to the exterior of the hat, a hat pin provided with a smooth tapering point adapted to be passed 20 through the opposite side of the hat and the point of the pin brought into a position to extend into and be housed in concealed and protected position within the chamber of the protector, and means independent of the protector, and coöperating with the pin and hat for locking the pin against withdrawal.

4. A hat pin point protector embodying means mounted on and supported by the hat and provided with a smooth-walled chamber closed exteriorly of the hat and opened 30 interiorly thereof, said chamber being adapted to receive and inclose the point of a smooth tapering pointed pin passed through the opposite side of the hat, whereby the

smooth pin point is received and housed 35 within the chamber in a fully concealed and protected position.

5. Hat pin retaining means embodying a threaded shank provided at one end with a socket having a helical channel and adapted 40 to be passed through an aperture in a hat, and a lock nut, screwed onto the shank from the interior of the hat to secure the shank in position on the hat, in combination with a hat pin adapted to be passed through the 45 threaded shank and provided with a projection to engage the channel of the socket whereupon rotation of the pin causes the projection to traverse the helical channel and clamp the pin against withdrawal from 50 the retainer.

6. An assembly of the character described embodying a chambered pin point protector adapted to be secured at one side of a hat and provided with a smooth interior, a hat pin 55 retainer adapted to be secured to the other side of the hat, and a hat pin embodying a plurality of telescoping sections having smooth coacting surfaces and adapted to be passed through the retainer and project into 60 the interior of the protector, in combination with locking means associated with the retainer and the pin for locking the pin against inadvertent displacement.

In testimony whereof, I have signed my 65 name to the foregoing specification.

JOHN B. FITZPATRICK.
